BINDER MECHANISM

Frederick D. Pitt, River Forest, Ill., assignor to
Wilson-Jones Company, Chicago, Ill., a cor-
poration of Massachusetts

Application July 15, 1944, Serial No. 545,117

2 Claims. (Cl. 24—153)

1

This invention relates to a binder mechanism of the type comprising a base member having a pair of prongs adapted to project through a plurality of sheets and a compressor plate adapted to engage the prongs in binding relationship.

It is an object of this invention to provide a binder mechanism with a compressor plate that may be secured to the prongs of the base member and detached therefrom quickly and efficiently. It is a further object of this invention to provide a compressor plate capable of retaining the prongs of the binder mechanism without any sliding keepers. Other objects of this invention will become apparent upon reading the following description, taken in conjunction with the accompanying drawings, in which:

Figure 1 is a perspective view of one embodiment of my invention showing the binder mechanism attached to a plurality of sheets;

Figure 2 is a cross-sectional view taken along the line II—II of Figure 1;

Figure 3 is a top plan view showing the method of securing the compressor plate to the prongs of my binder mechanism;

Figure 4 is a perspective view showing the prongs of the base member bent over the sheets to be bound and the compressor plate in disassembled relationship; and

Figure 5 is a top plan view of a modified form of compressor plate.

In the drawings, the reference numeral 2 indicates a base member having a pair of sheet retaining prongs 3, 4, which may be integral with the base member, as illustrated in the drawings, or may be secured to the base member in any suitable manner. A compressor plate 5 is provided adjacent opposite ends with a pair of slots 6, 7 which extend inwardly from opposite longitudinal edges of the compressor plate and divide the compressor plate into a central portion 8 and two ends 9 and 10. One edge of the slot 6 is rounded off, as indicated at 11, to facilitate securing of the compressor plate to the prongs. One edge of the slot 7 is rounded off, as indicated at 12, similarly to the portion 11. In order to strengthen the compressor plate 5 each longitudinal edge of the compressor plate is provided with a reinforcing rib, the ribs 13 and 13' being opposite the slots 6 and 7, respectively.

The end 9 of the compressor plate 5 is provided with a pair of laterally protruding tongues 14 and 14' adapted to straddle the prong 3 when the compressor plate is assembled with the base member, as indicated in Figure 3. The opposite end 10 of the compressor plate 5 is rounded off,

2

as indicated at 15, to facilitate entrance of the end 10 under the prong 4 when the compressor plate 5 is pivoted downwardly from the full line position of Figure 3. The end 10 of the compressor plate is preferably provided with a projection 16 extending laterally beyond the rounded edge 15. The projection 16 forms a finger piece to facilitate disengagement of the compressor plate from the base member. The central portion 8 of the compressor plate 5 is offset along its longitudinal medial line to form a channel 17 for the reception of the prongs 3 and 4.

In operation, a plurality of sheets 18, preferably provided with apertures 19 and 19', is impaled on the prongs 3 and 4, and the prongs are then bent substantially flat against the top surface of the uppermost sheet. The end 9 of the compressor plate is slid under the prong 3 so that the tongues 14 and 14' will straddle the prong 3. This first step in the securing of the compressor plate to the base member may be accomplished by inserting the end 9 of the compressor plate under the prong 3, as indicated in the dotted line position of Figure 3, and then pivoting the compressor plate to the full line position of Figure 3 with the prong 3 fitting into the slot 6, or it may be accomplished by starting with the compressor plate parallel to the prongs and sliding the compressor plate laterally of the prongs with the prong 3 riding over the entering end 9 of the compressor plate and into the channel 17. After the prong 3 is engaged with the tongues 14 and 14', and the slot 6, the compressor plate is pivoted so that the end 10 can be inserted under the prong 4.

When the prongs 3 and 4 are bent downwardly against the uppermost sheet of the stack of papers to be bound they are often pressed inwardly so that the portion of the prongs 3 and 4 in the apertures 19 and 19', respectively, are not at right angles to the base member 2, but are inclined toward the inner edge of the aperture. In order to avoid the necessity for tediously rebending the prongs whenever this condition exists, I have made the compressor plate 5 shorter in length than the distance between the inner edges of the apertures 19 and 19' so that no particular care need be exercised in bending the prongs 3 and 4 against the papers to be bound and the compressor plate will always fit with its ends 9 and 10 underneath and between the bent over prongs 3 and 4.

In the embodiment of Figure 5 both ends 20 and 20' of the compressor plate 21 are made similar to the end 10 of the first described em-

bodiment so that either end of the compressor plate may be inserted under the prong 3 in securing the compressor plate to the base member. Either of the projections 22 or 22', similar to the projection 16, serves as a guide by its engagement with the edge of the prong when the compressor plate is moved into engagement with the base member.

Although I have described two embodiments of my invention in detail, it will be understood that the description thereof is illustrative, rather than restrictive, as many details may be modified or changed without departing from the spirit or scope of my invention. Accordingly, I do not desire to be restricted to the exact details of construction described, except as limited by the appended claims.

I claim:

1. In a binder mechanism, a compressor plate having a pair of tongues on one end and having its other end rounded, a portion of said compressor plate projecting beyond said rounded end, said compressor plate having a pair of oppositely directed transverse slots adjacent said ends.

2. In combination, a base member, a pair of sheet retaining prongs projecting from opposite ends of said base member, a plurality of sheets of paper having apertures registering with said prongs impaled thereon, said prongs being bent over said sheets in substantial parallelism with said base member, and a compressor plate hav-

ing its ends fitting between and underneath said bent prongs and its central portion fitting over said prongs, said compressor plate being shorter in length than the distance between the inner edges of said apertures.
